UNITED STATES PATENT OFFICE.

JAMES BALLENGER WRIGHT, OF FRANKLIN, ILLINOIS, ASSIGNOR OF ONE-HALF TO
HAL HAROLD ROBERTS, OF JACKSONVILLE, ILLINOIS.

TIE-SETTING TOOL.

Application filed October 20, 1925. Serial No. 63,708.

This invention relates to tie setting tools and more particularly to a device of this character for holding a tie against the under surface of the rails of a right-of-way while 5 the earth is being tamped beneath the tie.

An important object of the invention is to provide a device of this character which not only acts as a support for the tie holding element but likewise serves as a gauge for 10 the rails.

A still further object of the invention is to produce a device of this character which may be readily transported from place to place and in which all of the elements employed in hoisting and holding the tie are substantially in the plane of the support 15 or gauge element.

These and other objects I attain by the construction shown in the accompanying 20 drawing, wherein for the purpose of illustration is shown a preferred embodiment of my invention and wherein:—

Figure 1 is a side elevation of a tie setting tool constructed in accordance with my in- 25 vention;

Figure 2 is a sectional view taken through the neck of the tie setting tool;

Figure 3 is a perspective of the neck and head of the tool.

Referring now more particularly to the drawing, the numeral 10 indicates a cross bar having at opposite ends thereof outwardly extended necks 11, the ends of which terminate in heads 12 having a flat under 30 face 13 for engagement with the top of the head of a rail and at the inner end of this face a depending shoulder 14 for engagement against the inner face of the rail. These flanges serve as limits for movement 35 of the sections of the rail toward one another and permit gauging of the rails which will be properly spaced when adjacent faces thereof contact with the shoulders 14.

Arising from the bar 10 at opposite ends 40 thereof are supports 15 to which are pivoted levers 16 overlying the bar 10 and having their inner ends arranged in close relation to one another. These inner ends may be held in adjusted position by means of a 45 flexible securing element, such as a chain.

To the outer ends of the levers 15 by means of links 18 are secured the handle 50

elements 19 of tie tongs 20 which straddle the neck 11 intermediate the end of the bar and the head.

It will be obvious that by the arrangement above described, the ends of the levers are conveniently spaced so that opposite ends of the tie may be lifted without the operator changing his position. It will also be obvious that due to the construction employed, the tongs are guided by the cross member and accordingly the cross member may be employed for properly aligning the tie. It will furthermore be obvious that the arrangement of these elements provides a very flat and readily handled structure which will not occupy much space upon a hand car or small work car employed for transporting tools.

Since this structure is obviously capable of a certain range of change and modification without materially departing from the spirit of the invention, I do not limit myself to such specific structure except as hereinafter claimed.

I claim:—

1. A tool of the character described comprising a bar, a restricted neck at each end of the bar having at its outer end a head including surfaces for engaging the inner face and top of a rail head, standards arising from the bar adjacent opposite ends thereof, levers pivoted upon said standards and tie tongs carried by the levers and straddling 55 said necks.

2. A tool of the character described comprising a bar, a restricted neck at each end of the bar having at its outer end a head including surfaces for engaging the inner face and top of a rail head, standards arising from the bar adjacent opposite ends thereof, levers pivoted upon said standards, tie tongs carried by the levers and straddling 60 said necks, said levers swinging in a plane including the bar, and flexible elements each secured at one end to the bar and adapted for adjustable engagement with the inner ends of said lever, said inner ends being arranged in close proximity.

In testimony whereof I hereunto affix my signature.

JAMES BALLENGER WRIGHT.
